DESIGN FOR A PIPE COUPLER

George C. Thomas, Jr., Elizabeth, N. J., assignor
to The Thomas & Betts Co., Elizabeth, N. J.,
a corporation of New Jersey

Application April 29, 1939, Serial No. 84,673

Term of patent 14 years

To all whom it may concern:

Be it known that I, George C. Thomas, Jr., a citizen of the United States of America and residing at Elizabeth, in the county of Union, and State of New Jersey, have invented a new, original, and ornamental Design for Pipe Coupler, of which the following is a specification, reference being had to the accompanying drawing, forming a part thereof.

Figure 1 is a top plan view of the pipe coupler

showing my new design. The operating nuts at each end are identical, and one is turned at a different angle from the other to more clearly show their appearance.

Figure 2 is an end view of the pipe coupler.

I claim:

The ornamental design for a pipe coupler, as shown and described.

GEORGE C. THOMAS, JR.
